CLAIM

The ornamental design for a cup, as shown and described.

DESCRIPTION

FIG. 1 is a top perspective view of our new design for a cup; FIG. 2 is a front view thereof, the back view being identical thereto;

FIG. 3 is a right side view thereof; the left side view being identical thereto;

FIG. 4 is a top plan view thereof; and,

FIG. 5 is a bottom plan view thereof.

The evenly spaced broken lines shown throughout these figures are for the purpose of illustrating unclaimed portions of the cup and form no part of the claimed design.
